METHOD OF AND APPARATUS FOR
WAVING HAIR

Adelbert E. Bronson, Shaker Heights, and Leonard S. Speth, Cleveland, Ohio, assignors to Adelbert E. Bronson, Jr.

Application January 8, 1943, Serial No. 471,694

9 Claims. (Cl. 132—36)

1

This invention relates to the waving of hair upon the human head and more particularly to an improved method and apparatus for producing a so-called "permanent wave." This application is in part a continuation of our earlier and now abandoned application Serial No. 405,774, filed August 7, 1941.

An object of this invention is to provide a novel method by which permanent waves having a desired softness and lustre can be given more quickly than heretofore and with greater safety and comfort for the patron, and which can be carried out by means of relatively simple and inexpensive apparatus utilizing stored heat and confined steam.

Another object of the present invention is the provision of a new and improved method of waving hair to produce a so-called "permanent wave" wherein the wound strand of hair, with a suitable waving solution, is enclosed within a heat-insulated housing or enclosure containing a heating element and such element is quickly raised to the desired temperature by electric heating whereupon the electric heating is discontinued and the waving operation is thereafter carried out or continued by the heat retained in the heating element and the insulated enclosure.

A further object of this invention is to provide a novel method of giving permanent waves in which a sufficient amount of heat is electrically supplied within a very brief time interval to a heat insulated enclosure containing a tensioned strand of hair and a suitable waving solution, to cause the solution to be substantially immediately converted into steam, and discontinuing the electric heating and completing the waving operation with the heat retained in the insulated enclosure and with said steam substantially confined in the enclosure.

Another object of this invention is the provision of simple, inexpensive and reliable equipment for practicing the present method.

Still another object of the invention is to provide novel hair waving apparatus including a heat-insulated and steam-retaining enclosure adapted to receive a tensioned strand of hair with a suitable waving solution, and also embodying means for electrically charging the enclosure within a very brief predetermined time interval with sufficient heat to convert the solution into steam and to complete the waving operation.

Further objects and advantages of the invention will be apparent, to those skilled in the art to which the invention relates, from the following description of the preferred method and apparatus.

2

tus for carrying out the same described with reference to the accompanying drawings forming a part of this specification in which:

Fig. 1 is a perspective view showing one form of our improved hair waving apparatus with the heat-insulated enclosure in assembled relation and with a strand of Croquignole-wound hair therein being waved according to the present method;

10 Fig. 2 is a longitudinal sectional view taken through the assembly as indicated by section line 2—2 of Fig. 1;

Fig. 3 is a transverse sectional view taken through the assembly as indicated by section line 15 3—3 of Fig. 2;

Fig. 4 is a plan view of the clamp showing the same opened;

Fig. 5 is an end view of the clamp;

Fig. 6 is a plan view looking into the housing 20 and showing the same with the heating element removed;

Fig. 7 is an end view of the housing with portions thereof broken away;

Fig. 8 is a perspective view of the heating element removed from the housing;

Fig. 9 is a detached view showing one of the retaining springs for the heating element;

Fig. 10 is a detached view showing one of the bars of the clamp disassembled and with portions 30 broken away;

Fig. 11 is an end view of the current supply plug or connector;

Fig. 12 is an elevation showing other waving apparatus for carrying out our method and in 35 which the heat is supplied inductively;

Fig. 13 is a longitudinal sectional view taken through such apparatus;

Fig. 14 is a transverse sectional view taken on line 14—14 of Fig. 13; and

40 Fig. 15 is another transverse sectional view taken on line 15—15 of Fig. 13.

Our hair waving method and apparatus hereinafter described in detail is applicable to both "Croquignole" waving and "spiral" waving. The 45 apparatus shown in Figs. 1 to 11 inclusive of the drawings is especially suitable for waving hair according to the so-called "Croquignole" method, the distinguishing characteristic of which is the fact that the hair is divided into flat strands which are wound from their free ends toward the scalp upon suitable curlers. Fig. 1 shows our improved waving apparatus applied to such a flat strand 10. This apparatus comprises, in general, a clamp 11 adapted to be supplied to the strand 50 55 adjacent the scalp, and a housing 12 adapted to

cooperate with the clamp to form a heat-insulated and steam-retaining enclosure for the wound strand and which housing contains an electric heating element 13. As will be described more in detail hereinafter, the heating element 13 is supplied with heating current for only a relatively short interval of time. The current is preferably a low voltage-high amperage current which quickly brings the heating element to the desired temperature, whereupon the current supply is discontinued and the waving operation is carried out or continued with the retained heat.

In carrying out our improved method with waving apparatus such as that disclosed in Figs. 1 to 11 inclusive, the hair is divided into a plurality of the flat strands 19 and one of the clamps 11 is applied to each such strand adjacent the scalp. A suitable curler, such as the curler 14 shown in this instance, is applied to the end of each strand and the strand wound thereon by a winding operation which brings the curler adjacent the clamp. The curler is then placed on or connected with the clamp and the wound strand is tensioned or stretched. A suitable waving solution is preferably applied directly to the strand either during or after the winding thereof, although it may be applied in any manner known in the art. The waving solution distributes itself throughout the wound strand and clings to the individual hairs more or less in the form of a relatively thin surrounding film which can be quickly converted into steam. The housings 12 are applied to the clamps, which also serve as covers of relatively low heat conductivity, so that each housing cooperates with its clamp to form an enclosure for the wound strand and which enclosure is sufficiently tight to substantially confine and retain the steam which is generated therein by vaporization of the waving solution.

A suitable current supply plug or connector member 15 is then applied to one of the assemblies thus formed so as to supply an electric heating current to the element 13 for the interval of time necessary to bring this element to the desired temperature, whereupon the connector member is removed from the assembly and shifted to the next assembly. The charging interval during which the heating current is supplied to the element 13 may be from five to fifteen seconds but should not exceed thirty seconds. The time interval can be varied and can be greater than fifteen seconds or less than five seconds, depending upon the electrical characteristics of the current and the requirements of the particular kind of hair being treated. During this brief charging interval the temperature of the element 13 is quickly raised to a relatively high value which may be on the order of five or six hundred degrees Fahrenheit and the waving solution, which as mentioned above is distributed through the wound strand and is more or less in the form of a film clinging to the individual hairs, is quickly converted or "flashed" into steam. The quantity or charge of heat thus supplied to the heating element and the assembly containing this element is preferably in excess of that required to quickly convert the waving solution into steam so that even though some heat is slowly dissipated from the assembly by radiation and conduction there will be sufficient heat to maintain the solution in the form of steam for a period of time long enough to complete the waving operation. Although the temperature within the assembly is quickly raised to a relatively high degree, as just explained, the heat insulating properties of the

assembly are such that the exterior thereof remains relatively cool permitting the assembly to be handled and used without danger or discomfort to either the operator or patron.

When the connector member 15 is removed from the assembly, the housing 12 is left connected to the clamp 11 so as to retain the heat and steam in the assembly and the waving operation is carried out or continued with the charge of heat which was supplied during the brief charging interval. The housing may be left closed for a period of a few minutes or several minutes, depending upon the requirements of the hair being treated. During this period, or for a substantial portion thereof, the heat charge maintains the solution in the form of steam and since the steam is confined in the assembly the wound and stretched hair is maintained quite damp or wet during the entire operation. We have found that a very satisfactory permanent wave can thus be imparted to the hair which retains a life-like softness and lustre in contrast to the dull, dry, and brittle condition of the waves produced by many of the usual methods employed, in which heat is supplied continuously and the wrapping applied to the wound hair permits the escape of steam and the consequent loss of the waving solution.

The clamp 11 may comprise a pair of cooperating bars 17 and 18 and a pair of end links 19 and 20. The bars 17 and 18 may comprise metal inserts 17a and 18a having soft rubber sleeves or coverings 17b and 18b thereon. The end links 19 and 20 may be formed of a non-metallic substance such as a molded electrically insulating material of suitable composition and may have grooves therein into which the ends of the metal inserts 17a and 18a may extend. The ends of the insert 18a may have bayonet slots 18c formed therein in which pins 21 engage for hingedly connecting the ends of the insert with the links 19 and 20. One end of the insert 17a may also have such a bayonet slot 17c therein which receives one of the pins 21 to form a hinged connection between this insert and the link 19. The other end of the insert 17a may have a recess 22 therein adapted to receive the latch portion 23 of the locking member 24 which is pivotally mounted in the groove of the link 20.

In addition to providing hinge connections between the bars 17, 18 and the end links 19, 20 the bayonet slots 17c and 18c and the pins 21 extending transversely of the slots of the end links also provide a means for easily assembling the parts of the clamp. Portions of the rubber coverings 17b and 18b normally overlie and close the bayonet slots but can be distorted or shifted on the inserts 17a and 18a to uncover the slots to permit the insertion or removal of the pins 21. These pins can be readily inserted into or removed from the bayonet slots when the bars are swung into substantial alignment with the end links.

The end links 19 and 20 have projecting brackets 19a and 20a formed thereon adapted to support the curler 14 which, in this instance, is in the form of a mandrel 14a having trunnions 14b and 14c at the outer ends thereof. A clip 14d may be hinged to the mandrel 14a to cooperate with the latter in clamping the end of the strand of hair. The trunnion 14b may be of rectangular form so as to hold the mandrel against unwinding when this trunnion is engaged in a similarly shaped recess 19b of the bracket 19a. The mandrel 14a may be rotatable in one direction only relative to the trunnion 14b to facilitate the

tightening and stretching of the wound strand of hair after the curler has been mounted in the brackets 19a and 20a. The round trunnion 14c may be integral with the mandrel 14a and is adapted to be rotated in the recess of the bracket 20a by the application of a suitable tool to the slot 14e. The recess 20b of the bracket 20a may be of rectangular shape so that it will accommodate the trunnion 14b if it should be desirable to reverse the position of the curler relative to the clamp.

The housing 12 may be molded or otherwise formed from a suitable electrically insulating material or composition which is preferably also a poor heat conductor and, as shown in the drawing, may be an elongated box-like structure which is open on one side thereof. The housing is of a size and shape such that it will readily receive the curler 14 with the strand of hair wound thereon and such that the clamp 11 will form a more or less steam-tight cover or closure for the open side of the housing when the housing is connected to the clamp as shown in Fig. 1. The housing may be connected with the clamp by any suitable means such as the releasable spring latch members 25 mounted on the ends of the housing.

The heating element 13 may comprise an elongated metal shell 13a of channel-like cross-sectional shape and a heating coil or resistance wire 13b extending along the bottom of the channel recess. The metal shell may be formed of doubled sheet metal bent to the desired shape with portions of the two thicknesses spaced apart to provide a longitudinal chamber or recess 13c in which the coil 13b is disposed. This shell is preferably made of a metal or alloy having a high heat conductivity, such as copper, silver or aluminum, so that the heat charge will be absorbed quickly from the coil 13b and will be quickly delivered to the hair and waving solution. The ends of the heating coil may be connected to ears 26 and when the element is assembled in the housing 12, threaded openings provided in these ears are engaged by screws 27 which extend through the walls of the housing. The heads of the screws 27 provide contacts or terminals accessible from the exterior of the housing to which the connector member 15 can be applied for supplying electric heating current to the element 13. As shown in Fig. 3, the heating element 13 is arranged in the housing 12 opposite the open side thereof so that when the housing is applied to the clamp 11, the channel recess will snugly receive the curler with the wound strand of hair thereon but preferably without having the wound hair in actual contact with the heating element. The tops of the side portions of the shell of the heating element may be deflected outwardly to form the beveled sections or inclined flanges 13d whose free edges lie against or adjacent the walls of the housing when the heating element is assembled therein.

It is very important to retard the transfer of heat from the element 13 to the housing 12, and therefore we arrange the element in the housing so that it will, with the exception of the edges of the flanges 13d, be separated from the bottom and side walls thereof by an intervening heat-insulating air space 28. To maintain this air space we support the element 13 on shouldered lugs 29 which are located on the bottom wall of the housing adjacent the ends thereof and are engaged by the ends of the element. We may also provide the side walls of the housing with

lugs or ribs 30, the tops of which are engaged by the inclined flanges 13d to prevent transverse rocking or lateral shifting of the element in the housing. The element may be held in the housing and against the lugs 29 and 30 thereof by springs 31 which assume an inwardly bowed position at the ends of the element when they are assembled in the housing. These springs have retaining ears 31a which extend into the channel recess of the heating element. The fact that the brackets 19a and 20a and the end links 19 and 20 of the clamp are made of a non-metallic substance will also retard the transfer of heat from the curler 14, and the soft rubber sleeves 17b and 18b of the bars 17 and 18 will act as gaskets in forming a steam-tight seal between the housing and clamp.

Electric heating current of the desired low-voltage and high-amperage characteristics may be supplied to the element 13 by any suitable means such as the apparatus shown in Fig. 1 and which includes a connector or plug 15 adapted to be applied to the housing 12 of each assembly. This connector has a pair of arms 32 adapted to be spread apart to engage over the terminal screws 27 by pressure applied to a pair of buttons 33, and to resiliently grip these screws when the buttons are released. The arms 32 may carry flexible contacts 34 connected with a pair of load conductors 35 through which the heating current is supplied to the terminal screws 27 when the connector is applied to the assembly as shown in Fig. 1.

The current supply means may also include a combined timer and transformer unit 38 which may be located at any convenient point and with which the connector 15 is connected by the flexible cable 38a. The unit 38 may be connected with the usual A. C. lighting circuit by the conductor cord 38b and may contain a suitable transformer 38a and a suitable time switch 38b. This time switch can be manually set for the desired time interval during which current is to be supplied to the element 13. A push button switch 36 embodied in the connector 15 is connected with the time switch 38b of the unit 38 by a pair of conductors 37 so that when this push button switch is actuated, current will be supplied to the heating element 13 through the load conductors 35 and under the control of the time switch. When the desired interval for charging the assembly with heat has elapsed, the time switch interrupts the circuit and the heating current is cut off until the push button switch 36 is again actuated.

In Figs. 12 to 15 inclusive we show other apparatus for carrying out our hair waving method and which is especially applicable to "spiral" waving wherein a generally round strand of hair is wound spirally on the curler. As will be presently explained more in detail, the spirally wound strand is enclosed in a non-metallic heat-insulated housing, with a suitable waving solution, and a metal heating element in the housing is then heated inductively to quickly bring the temperature thereof to a desired value, whereupon the inductive heating is discontinued and the waving operation is continued or completed with the retained heat and the confined steam produced by vaporization of the waving solution.

As shown in Figs. 12 to 15 inclusive, such other apparatus includes an elongated tubular housing 40 composed of cooperating non-metallic housing members or sections 41 and 42. The housing member 42 may be closed at its outer end by

transverse end wall 42a and at its inner end may have a sleeve portion 42b within which the end of the housing member 42 frictionally engages for holding the two housing members in connected or assembled relation. This apparatus also includes a suitable curler 43 on which the strand of hair 44 may be spirally wound, as shown in Fig. 13. The curler 43 may be of a well known type on which the spirally wound strand 44 can be tightened and stretched after the strand has been tied thereon by the strings 45 and 46.

The curler 43 with the strand of hair wound thereon is arranged in the housing 40 to extend axially or longitudinally thereof and may be supported in the housing by providing the housing members 41 and 42 with suitably recessed portions 41a and 42c in which the ends of the curler supportingly engage. To accommodate the strand 44 the housing member 41 may be provided with a slot 47 through which the strand extends when the curler is in assembled position in the housing 40.

As in the case of the waving apparatus disclosed in Figs. 1 to 11 inclusive and above described, it is important to insulate the housing 40 against the loss of heat, and for this purpose we provide a heat-insulating air space 48 which surrounds the hair strand and curler. This air space may be formed by mounting a sleeve 49 in the housing member 42 in spaced relation to the wall thereof, as shown in Fig. 13. This sleeve may be supported in the housing member 42 by an annular shoulder 50 formed on the end wall 42a and by an internal flange 51 located adjacent the sleeve portion 42b, and may be retained in the housing member in any suitable way, as by a press fit with such shoulder and flange.

As mentioned above, the housing members 41 and 42 are of non-metallic construction and may be molded or otherwise formed from a suitable plastic or other non-metallic composition of relatively low heat conductivity. The main purpose in making the housing sections non-metallic is to enable the hair strand to be heated by heat supplied inductively to a heating element contained in the housing without also causing heating of the housing. Such heating element may be provided in the housing 40 by using a metal curler for the curler 43, or by using a metal sleeve for the sleeve 49. If it should be desirable to supply heat to the strand 44 both internally and externally, then both the curler 43 and the sleeve 49 would be made of metal. If heat is to be supplied to the strand internally only, the curler 43 would be made of metal and the sleeve 49 would be made of a plastic or other non-metallic composition. On the other hand, if heat is to be supplied to the strand externally only, then the curler 43 would be made of plastic or other non-metallic composition and the sleeve 49 would be made of metal.

The inductive heating of the metal heating element or elements in the housing 40 may be accomplished by bringing a suitable wire coil or helix 52 into temporary surrounding relation to the housing 40, as shown in Fig. 12, and passing a high-frequency electric current through the coil. The coil 52 may be provided with an insulating handle 53 by which the coil can be conveniently moved into and out of surrounding relation to the housing 40. The ends of the coil 52 may extend into the handle 53 for connection with a conductor cord 54 by which the coil may

be connected with a suitable high-frequency transformer.

In carrying out our method with the waving apparatus illustrated in Figs. 12 to 15 inclusive, a number of strands of hair are wound on the curlers 43 and enclosed in the individual housings 40 with suitable waving solution. When a desired number of such assemblies have been prepared, the coil 52 is energized from the transformer and is applied to the assemblies in succession in the manner shown in Fig. 12. The coil 52 need remain in surrounding relation to each assembly for an interval of time which does not exceed 30 seconds, and which in some instances may be only a few seconds or a fraction of a second. During this interval the assembly is charged with the amount of heat needed to complete the waving operation, and the temperature in the assembly is quickly raised to a relatively high value which quickly causes the waving solution to be "flashed" or vaporized into steam and maintained in the form of steam for a long enough period to complete the waving of the strand. The housings 40 are not opened immediately after the removal of the coil 52, but are left closed for a desired period of time during which the waving operation is continued or completed by the heat and steam retained in the assembly.

As is usual in the spiral winding of strands of hair, a soft rubber insulating pad 55 and a suitable clamp 56 may be applied to the hair strand at a point adjacent the scalp prior to the winding of the strand on the curler 43. The pad 55 may have an opening therethrough to accommodate the strand 44, and the clamp 56 may have a bracket-like portion 56a thereon for supporting engagement with the housing 40. A reversely extending tongue 56b may be formed on the bracket 56a to overlie the slot 47 to substantially close the latter and prevent the escape of steam from the assembly.

Although we have stated that our method, as disclosed in connection with the form of apparatus shown in Figs. 1 to 11 inclusive, is especially applicable to "Croquignole" waving, it will be understood that this method is also readily applicable to "spiral" waving. On the other hand, we have stated that our method, as disclosed in connection with the form of apparatus shown in Figs. 12 to 15 inclusive, is especially applicable to "spiral" waving, but it will be understood that this method is also applicable to "Croquignole" waving.

From the foregoing description and the accompanying drawing it will now be readily understood that we have provided an improved hair waving method which can be carried out with a smaller amount of equipment than has heretofore been needed and which does not require the customer to be connected up to a waving machine during the treatment of the hair. With our method and apparatus a permanent wave having a desired softness and lustre can be given more quickly because after the strands of hair have been wound and placed in the enclosure assemblies, it is only necessary to apply the electrical connector or coil to each assembly for a few seconds to bring the heating element to the desired temperature. Furthermore, the heat used during the waving operation is contained within the heat-insulated assemblies which remain relatively cool on their exterior and the customer is not subjected to the discomfort heretofore ex-

perienced from radiated heat when exposed or external heaters have been used.

While we have illustrated and described the improved permanent waving method and apparatus of our invention in a more or less detailed manner, it will be understood, of course, that we do not wish to be limited to the particular operations and apparatus herein disclosed, but regard our invention as including such changes and modifications as do not constitute a departure from the spirit of the invention and the scope of the appended claims.

Having thus described our invention, we claim:

1. The method of permanently waving hair which comprises winding and tensioning a strand of hair on a curler, enclosing the wound strand of hair with a suitable hair waving solution in a heat-insulated steam-retaining assembly which also contains a heating element, supplying heat-producing energy to said heating element at a rate to quickly raise the temperature of the heating element sufficiently to substantially immediately convert said solution into steam, and discontinuing the supply of energy to said heating element and continuing the waving process with the heat retained within said insulated assembly and with said steam confined therein.

2. The method of waving hair, which comprises enclosing a wound and tensioned strand of hair in a heat-insulated steam-retaining enclosure together with a suitable waving solution and an electric heating element of the resistance type, temporarily connecting said element with a source of relatively low voltage-high amperage heating current so as to quickly supply the assembly with a charge of heat and substantially immediately convert the solution into steam, and continuing the waving operation with the retained heat and confined steam after disconnecting the element from said source.

3. The method of waving hair comprising separating the hair into strands and applying clamps to the strands at a point adjacent the scalp, winding and tensioning the strands on curlers, enclosing each wound strand in a heat-insulated steam-retaining enclosure together with a suitable waving solution and a heating element adapted to be heated by electrical energy, applying a connector member to and removing the same from the enclosures in succession so as to temporarily connect each heating element with a source of electrical energy for a brief interval to supply each enclosure with a charge of heat sufficient to quickly convert said solution into steam and to maintain the solution in the form of steam long enough to complete the waving operation, and continuing the waving operation after the removal of the connector member and with the heat and steam retained in the enclosures.

4. The method of waving hair comprising separating the hair into strands and applying clamps to the strands at a point adjacent the scalp, winding and tensioning the strands on curlers, enclosing each wound strand in a heat-insulated steam-retaining enclosure together with a suitable waving solution and a resistance-type electric heating element having terminals accessible from the outside of the enclosure, applying a connector member to and removing the same from the enclosures in succession so as to temporarily connect each heating element with a source of relatively low voltage-high amperage heating current for a brief interval to supply each enclosure with a charge of heat sufficient to

quickly convert said solution into steam and to maintain the solution in the form of steam long enough to complete the waving operation, and continuing the waving operation after the removal of the connector member and with the heat and steam retained in the enclosures.

5. The method of waving hair which comprises enclosing a wound and tensioned strand of hair in a non-metallic steam-retaining enclosure together with a waving solution and a metallic heating element, inductively supplying heat-producing energy to said heating element at a rate to bring said element to a desired temperature and to convert said solution into steam within a brief interval, and discontinuing the supply of such energy and continuing the waving operation with the heat and steam retained in the enclosure.

6. In hair waving apparatus, a clamp adapted to be applied to a strand of hair, a curler for winding the strand, a housing adapted to be connected to said clamp to form therewith a steam-retaining enclosure for the wound strand, an electric heating element mounted in the housing and located in said enclosure with heat-insulating air space between the element and the housing walls, and means for temporarily connecting said element with a source of heating current including a connector member adapted to be detachably applied to said terminals.

7. In hair waving apparatus, a clamp adapted to be applied to a strand of hair, a curler for winding the strand, a housing adapted to be connected to said clamp to form therewith a steam-retaining enclosure for the wound strand, an electric heating element mounted in the housing and located in said enclosure with heat-insulating air space between the element and the housing walls, and means for temporarily connecting said element with a source of heating current including a connector member adapted to be detachably applied to said terminals, said element having a metal shell forming a body for retaining heat after the element has been disconnected from said current source.

8. In hair waving apparatus, a clamp adapted to be applied to a strand of hair, a housing having side and end walls but being open on one side thereof, a curler for winding said strand, means for connecting said housing with said clamp so that the latter forms a closure for said open side, a heating element disposed in said housing opposite said open side and having terminals accessible from the outside of the housing, said heating element being insulated from the housing by air space and being transversely curved to receive the wound strand therein, and means for temporarily connecting said element with a source of heating current including a connector adapted to be detachably applied to said terminals.

9. In hair waving apparatus, a pair of cooperating housing and cover members adapted to form an enclosure for a wound strand of hair, said cover having means thereon for supporting the wound strand, and a transversely curved electric heating element of the resistance type mounted in said housing member so as to receive the wound strand when the cover member is applied to the housing member, said heating element having terminal connections accessible from the outside of the enclosure.
